CLAIM

We claim the ornamental design for a charging cradle, as shown and described.

DESCRIPTION

FIG. 1 is a top, front, left side perspective view of a charging cradle of our new design;

FIG. 2 is a bottom, rear, right side perspective view thereof;

FIG. 3 is a top plan view thereof;

FIG. 4 is a bottom plan view thereof;

FIG. 5 is a rear view thereof;

FIG. 6 is a front view thereof;

FIG. 7 is a left side view thereof; and,

FIG. 8 is a right side view thereof.

The broken lines in the drawings are for the purpose of illustrating portions of the charging cradle that form no part of the claimed design.
